(57) **CLAIM**

The ornamental design for a lighting apparatus, as shown and described.

DESCRIPTION

FIG. 1 is a front view of a lighting apparatus showing our new design;

FIG. 2 is a top view thereof;

FIG. 3 is a bottom view thereof;

FIG. 4 is a right side view thereof;

FIG. 5 is a perspective view thereof; and,

FIG. 6 is a cross-sectional view thereof taken along the line 6-6 in FIG. 2.

The broken lines on the drawings represent environment only and form no part of the claimed design.

A rear view is omitted because it is the same as the front view. A left side view is omitted because it is the same as the right side view

1 Claim, 4 Drawing Sheets
